OTHER PUBLICATIONS

Exhibit A. Curtis Wagner Co., Inc., Houston, Texas. Shows thick, stiff shiny red plastic pot cover with large scalloped border. (Photograph) Date unknown.

Exhibit B. Jacobson Pot Cover Company of Scranton, Pennsylvania. Advertising literature. Date of first use unknown.

Exhibit C. Photograph of pot cover, manufacturer unknown, but very similar to C21 on Exhibit B (Jacobson literature). Date unknown.

Exhibit D. Photocopy of pot cover ("Platform Pot Dresser") made by John Raisen Corp., San Francisco, California. Date of first use unknown.

Exhibit E. Photograph of 2-part pot cover system made by Floral Decor, subsidiary of John Henry Co., Lansing, Michigan. Date unknown.

Exhibit F. Photo of pot cover made by a Holland company (K.P.L.). Date of first public use believed to be late 1984.

Exhibit G. "The Glass of Frederick Carder", copyright 1971 by P.V. Gardner, showing various styles of glass basket-like vases or containers.

Exhibit H. "Speed Cover®" brochure, published in 1983 by Applicants, showing various pot covers for sale.

Exhibit I. "Speed Cover®" brochure, published in 1983 by Applicants, showing various pot covers for sale.

Exhibit J. Item published in 1936 by Gellman Bros., Minneapolis, Minnesota. Shows an assortment of paper hats.

Exhibit K. Photo of various other flower pot wrappings, sold in rolls or sheets and used in the floral industry for years. Date unknown.

(List continued on next page.)

Primary Examiner—Jeffrey Asch*Attorney, Agent, or Firm*—Dunlap & Codding, P.C.[57] **CLAIM**

The ornamental design for a flower pot cover, as shown and described.

DESCRIPTION

FIG. 1 is a perspective view of our new flower pot cover design;

FIG. 2 is an side elevational view;

FIG. 3 is a top plan view; and,

FIG. 4 is a bottom plan view.

The flower pot cover has no substantial thickness.
